UNITED STATES PATENT OFFICE.

HARRY S. McCORMACK, OF NEW YORK, N. Y., ASSIGNOR TO UNDERWOOD TYPEWRITER COMPANY, OF NEW YORK, N. Y., A CORPORATION OF NEW JERSEY.

TYPE-WRITING MACHINE.

No. 887,419.

Specification of Letters Patent. Patented May 12, 1908.

Application filed May 2, 1907. Serial No. 371,377.

2 all whom it may concern:

Be it known that I, HARRY S. McCORMACK, a citizen of the United States, residing in New York, in the county of New York and State of New York, have invented certain new and useful Improvements in Type-Writing Machines, of which the following is a specification.

This invention relates to the special paper-feeding devices of typewriting machines, designed to facilitate the writing of bills and simultaneously recording them in the manner commonly known as "condensed charging."

The object of my invention is to provide improved, simplified and easily operable means for rotating the platen back to receive a new bill and then forward to bring the bill to printing position.

According to the present invention, a crank is mounted upon a platen frame, but out of connection with the platen; and a single swinging movement of the crank accomplishes the two-fold object of connecting the crank to the platen, and then rotating the platen. It is thus possible by a single crank movement to rotate the platen back to the desired position, this being an extremely simple operation.

In the preferred form of the invention, the crank is mounted loosely upon the platen, and a pawl is pivoted upon the crank in position to engage a toothed wheel, the latter being fixed to the platen. A spring normally holds the pawl out of engagement with the toothed wheel, but a single movement of the crank throws the pawl into engagement with the toothed wheel, and such engagement is mechanically maintained until the crank is swung back to normal position, whereupon said spring throws the pawl out of engagement with the toothed wheel, and also serves to latch the crank in its normal position.

In the accompanying drawings, Figure 1 is a plan view of the platen frame of an "Underwood" typewriting machine provided with my improvements. Fig. 2 is an end elevation of the platen-controlling devices, made the subject of this application; the crank being shown as connected to the platen and rotating the same backwardly to the proper position for the insertion of a bill in the machine. Fig. 3 is a view similar to Fig. 2, but showing the crank in a normal position of disuse, to permit rotation of the platen in either direction independently of the

crank. Fig. 4 is an enlarged perspective view of the hub-portion of the crank and the pawl thereon. Fig. 5 is a longitudinal section showing the crank-mechanism.

The usual cylindrical platen 1 of an Underwood typewriting machine is fixed upon an axle 2 journaled in the ends 3, 4, of a platen frame 5, the end of the axle projecting through the platen frame end 3 having a finger-wheel 6 thereon by means of which the platen may be rotated forwardly or backwardly to an unlimited extent. The platen is also provided with the usual line-spacing devices, of which a toothed line-space wheel 7 and a yielding detent 8 therefor are seen at Fig. 1. Said line-space wheel is advanced intermittently by a pawl and lever, not shown. Upon the other projecting end of the platen axle is secured by screws 9 a hub or sleeve 10 in the outer end of which is secured a short stem 11, by means of a pin 12, said stem being in effect a continuation of the platen axle 2 and carrying a finger wheel 13. Upon the stem 11 is secured a wheel 14 having teeth 15 agreeing in number with the teeth on the line-space wheel 7. This wheel is rigidly secured to the stem 11 by a pin 15.

The wheel 14 is rotatable by means of a pawl 16 having a tooth 17 to engage the teeth 15 of the wheel, but normally disengaged therefrom, as seen at Fig. 3, to permit independent rotation of the wheel 14 and the platen 1. Said pawl is pivoted at 18 to a crank 19 having a hub 20 to fit upon the outer end of the sleeve 10.

In order to effect backward rotation of the platen the crank is swung from its normal rear position at Fig. 3 forwardly as at Fig. 2, the first portion of the movement of the crank causing the tooth 17 of the pawl to move into engagement with the teeth 15 of the wheel 14. Said pawl carries a pin 21, which is normally pressed by a spring 22 into a notch 23 formed in a motionless disk-like member 24 mounted upon the outer portion of the sleeve 10. When the crank starts forwardly, said pin 21 is pulled out of the notch 23, and thereafter travels in an annular groove 25 cut in the face of the member 24 concentric with the platen axle 2, the outer wall of said groove acting to confine the pawl so that its tooth 17 cannot escape from the wheel 14, and hence the platen must rotate backwardly and forwardly with the crank 19, which is provided with a finger-piece 26.

The movements of the crank are limited by a stop 27 mounted upon an arm 28 which is also pivoted upon the sleeve 10, said arm being confined between the crank hub 20 and the grooved disk-member 24, and all three being confined between the wheel 14 and a shoulder 19 formed upon the sleeve 10. The stop is provided with a releasable pin 30 to engage any of a series of holes 31 formed in the grooved-member 24, the latter being prevented from rotating by means of a link 32 pivoted at 33 to the member 24 and at 34 to the platen frame.

The stop 27 having been set to the required position, as at Figs. 2 and 3, the handle 26 is grasped by the operator to swing the same towards the front of the carriage and downwardly, as shown by the arrow at Fig. 2. The initial movement of the crank forces the pawl to engage the wheel 14, so that the latter and the platen are caused to rotate with the crank in a direction to turn the platen backwardly to receive a new bill, this motion of the platen continuing until the crank 19 is arrested by the stop 27. Upon the bill being inserted, the crank is swung through its return stroke back to initial position, the pin or projection 21 riding in contact with the outer wall of the groove 25, which keeps the pawl 16 locked to the wheel 14. At the terminal portion of the return stroke of the crank, the pin 21 is engaged by the spring 22 and snapped up into the notch 23, thereby releasing the wheel 14 and also arresting the crank, which thereafter is yieldingly held by said spring in normal position, as at Fig. 3.

Thus, it will be seen, that by a simple mechanism, provision is made whereby the operator, when desiring to rotate the platen backwardly, needs only to grasp the crank, and swing it in a single direction about the platen axis 2 automatically effecting the locking of the crank to the platen, and maintaining such lock connection until the crank is swung back again, as far as it will go, whereupon the first line of writing may be begun upon the bill.

Variations may be resorted to within the scope of the invention, and portions of the improvements may be used without others.

Having thus described my invention, I claim:

1. In a typewriting machine having a revolute platen, the combination with a toothed wheel connected to the platen to revolve therewith, of a platen-oscillator, a tooth normally disengaged from said toothed-wheel, means to enable a single movement of said platen-oscillator first to effect engagement between said tooth and said toothed-wheel, and then to revolve the wheel and platen, and means to maintain the engagement of the tooth and the wheel during both the forward and backward strokes of the oscillator.

2. In a typewriting machine having a revolute platen, the combination with a toothed wheel connected to the platen to revolve therewith, of a platen-oscillator, a tooth normally disengaged from said toothed-wheel, means to enable a single movement of said platen-oscillator first to effect engagement between said tooth and said toothed-wheel, and then to revolve the wheel and platen, means to maintain mechanically the engagement of the tooth and the wheel during both the forward and backward strokes of the oscillator, and means to effect disengagement of the tooth from the wheel upon return of said oscillator to normal position.

3. In a typewriting machine having a revolute platen, the combination with a toothed-wheel connected to the platen to revolve therewith, of a pawl having a tooth, a spring normally holding said pawl out of engagement with said toothed-wheel, a rotatable platen-oscillator, means for enabling the initial portion of the rotation of said oscillator to move said pawl tooth into engagement with said wheel, and for enabling the continued rotation of said oscillator to act through said pawl to revolve said platen, a stop for arresting the movement of the platen and oscillator, and means to maintain the engagement of the pawl with the wheel during both the forward and backward strokes of the oscillator.

4. In a typewriting machine having a revolute platen, the combination with a toothed-wheel connected to the platen to revolve therewith, of a crank mounted for revolution with said toothed-wheel, a pawl upon said crank and normally out of engagement with said toothed-wheel, means for enabling the crank by a swinging movement thereof to force said pawl into engagement with said toothed-wheel, and means for maintaining mechanically the engagement of the pawl and wheel, during the excursion of said crank away from and back to normal position.

5. In a typewriting machine having a revolute platen, the combination with a toothed-wheel connected to the platen to revolve therewith, of a crank mounted for revolution with said toothed-wheel, a pawl pivoted to said crank and normally out of engagement with said toothed-wheel, a spring for holding said crank stationary, and said pawl disengaged from said toothed wheel during the usual line-spacing movements of the platen, means for enabling a turning movement of the crank, to force said pawl into engagement with said wheel, means for mechanically maintaining the engagement of the pawl and wheel during the excursion of said crank away from and back to normal position, and a stop for limiting the initial stroke of the crank.

6. In a typewriting machine having a revolute platen and a platen axle, the combination with a toothed-wheel fixed upon said

axle, of a crank loosely supported to swing about said axle, a pawl pivoted to said crank, a pin projecting from said pawl, and a fixed part having a notch into which said pin is 5 pressed by a spring, both to hold the pawl away from the wheel, and also to hold the crank stationary, during the usual line-by-line revolution of the platen, said pin being releasable from said notch by means of a pull 10 on the crank, and said fixed part having a circular guiding surface concentric with said axle to engage said pin to lock the pawl to the wheel.

7. In a typewriting machine having a revolvable platen, the combination with a toothed-wheel connected to the platen, of a crank loosely supported to revolve with said toothed-wheel, a pawl pivoted to said crank, means to hold the pawl away from the wheel, and 15 also to hold the crank stationary during the usual line-by-line revolution of the platen, said crank being effective to force the pawl into engagement with the wheel, and a circular guiding surface concentric with the 20 wheel to lock the pawl to the wheel.

8. In a typewriting machine having a revolvable platen and a platen axle, the combination with a toothed-wheel fixed upon said 25

axle, of a crank loosely supported upon said axle, a pawl pivoted to said crank, means to 30 carry the pawl around said axle, a pin projecting from said pawl, and a fixed part having a notch into which said pin is pressed by a spring to hold the pawl away from the wheel, said crank being effective to force said 35 pin out of said notch and to engage the pawl with the wheel, and said fixed part having a circular guiding surface concentric with said axle to engage said pin to lock the pawl to the wheel.

9. In a typewriting machine having a revolvable platen and a crank normally disconnected from the platen, of means yieldingly holding the crank in normal position, so that a swing of the crank itself will release it from 40 said yielding means, means rendered effective at said releasing operation for connecting the crank to the platen, and means for mechanically maintaining the connection of the crank to the platen during the excursion of 45 the crank away from and back to normal position.
